UNITED STATES PATENT OFFICE.

HENRY O. FREEMAN, OF EDEN, IDAHO.

GRAIN SEPARATOR.

Application filed January 16, 1926. Serial No. 81,784.

My invention relates to improvements in grain separators, and it consists in the combinations, constructions and arrangements herein described and claimed.

5 An object of the invention is the provision of a simple and reliable separator structure which affords facilities for separating practically all the grain from straw and chaff.

10 A further object of the invention is the provision in a separator of a separator floor or table which has means for thoroughly breaking up masses of straw, grain and chaff as such masses move across the separator floor or table and for causing the straw, 15 chaff and grain to fall vertically at intervals during their passage across the separator floor or table, whereby practically all the grain will be detached from and separated from the straw and chaff.

20 Other objects and advantages of the invention will be apparent from the following description, considered in conjunction with the accompanying drawings, in which—

25 Figure 1 is a fragmentary longitudinal vertical sectional view of the improved grain separator.

Figure 2 is a relatively enlarged fragmentary transverse vertical sectional view of a portion of the grain separator.

30 Figure 3 is a fragmentary perspective view of one of the sections of the main separator floor.

The supporting structure of the separator may comprise side walls such as indicated at 1. While I show only one side wall 1, it will be understood that in practice a pair of the side walls 1 may be provided and disposed in spaced parallel relation. An upper separator floor generally indicated 40 at 2 extends between the side walls 1. This upper separator floor comprises a plurality of juxtaposed longitudinal sections, each of which is substantially U-shaped in cross sectional contour.

45 These sections 3 are arranged in a series which extend transversely of the supporting structure or body of the separator so that the outer flanges of the sections 3 that are next to the side members 1 are disposed flatwise against attaching and reinforcing bars 4, which are rigidly secured to the side walls 1. Fastening devices, such as indicated at 5 secure the outer flanges of the outer sections 3 to the reinforcing bars 4. The sections 3 50 between the outer sections 3 are relatively arranged so that the adjacent flanges of adjacent

sections 3 are in close contact with each other throughout their length and are fastened together by suitable fastening devices such as indicated at 6. The web portions of the respective sections 3 thus will be disposed at the same level. The web portions of these sections 3 are curved arcuately transversely thereof, the concavely curved surface thereof being uppermost. These web portions of the sections 3 are imperforate from their front ends for a short distance as indicated at 7 and are cut away at 8 for a short distance from the rear ends of the sections 3. The portion of the web of each section 3 that extends between the imperforate end portion 7 and the cut away portion 8 is formed with a longitudinally extending series of spaced apertures 9. These apertures are located along the longitudinal median line of the web portion of each section 3 and each opening 9 is produced by striking adjacent portions of the web of each section 3 upwardly and rearwardly at the front edge of each of the openings in the web of the section 3 and downwardly and forwardly at the rear edge of the same opening in the web portion of the section 3, thus producing the upwardly and rearwardly inclined tongues 10 at the front edges of the openings 9 and the 85 downwardly and forwardly inclined tongues 11 at the rear edges of the openings 9.

The flanges of each section 3 are symmetrically formed and each flange has relatively deep notches 12 cut therein at regularly spaced intervals along the length of the flange. The front wall of each notch 12 is substantially vertical as clearly shown in Figure 1. The portions of the flanges of each section 3 which extend between adjacent notches 12 have the edge portions thereof fashioned to incline rearwardly and upwardly from each notch 12 to the vertical wall of the notch 12 next at the rear thereof and these inclined edge portions of the flanges of each section 3 have spaced notches 13 produced therein, the front wall of each notch 13 being vertical and the other wall of each notch 13 being inclined upwardly and rearwardly. The respective notches 13 are the same depth and it thus will be manifest that the respective notches 13 which are located between adjacent notches 12 will be located at different levels, the bottom of each notch 13 other than the first notch 13 of a series being located at a slightly higher level than the preceding notch 13.

A secondary separator floor indicated generally at 14 may be supported between the side members 1 of the supporting structure of the device underneath the main separator floor 2. The secondary separator floor 14 comprises a series of channel-shaped longitudinal sections 15. The flanges of the side sections 15 are attached, as at 16 to attaching and reinforcing bars 17 which in turn are secured to the side walls 1 and adjacent flanges of adjacent sections 15 are secured together by fastening devices 18. The front end portion of the bottom or web portion of each section 15 is imperforate for a short distance as indicated at 19 in Figure 1 and the rear end portion of the web or bottom of each section 15 is cut away for a short distance from the rearward end of that section, as indicated at 20. The remainder of the bottom or web of each section 15 is formed with a longitudinally extending series of spaced openings 21 and so that a tongue 22 extends downwardly and forwardly from the rear edge of each opening 21 and a tongue 23 extends upwardly and rearwardly from the front edge of each opening 21. The flanges of each section 15 have notches 24 formed therein, the front wall of each notch 24 being substantially vertical and the rear wall of each notch 24 being inclined upwardly and rearwardly as clearly shown in Figure 1.

A screen 25 may be supported underneath the separator floor 14 rearwardly of the imperforate portions 19 of the bottoms of the sections 15 and forwardly of the cut away portions 20 of the bodies of the sections 15 of said separator floor. A delivery chute 26 having a forwardly and downwardly inclined bottom 27 may be supported underneath the screen 25 and a blower fan 28 may be supported in a housing 29 having a discharge outlet 30 from which air may be blown underneath the screen 25 and upwardly through the latter. The details of construction of the parts which are associated with the separator floors 14 and 2 may vary considerably from those illustrated without departing from the spirit and scope of the invention as will hereinafter more clearly appear.

The operation of the device is substantially as follows: A mass of grain, straw and chaff is discharged in any suitable known manner and by any suitable known means, none being shown, onto the forward end portion of the separator floor 2 and is moved rearwardly on the separator floor 2. The serrated edges of the flanges of the channel-shaped sections of the separator floor 2 will support the mass of straw, chaff and grain and will break up such mass since it will be obvious that as the mass progresses toward the rearward end of the floor 2, considerable vertical movement of the mass or particles thereof will take place as particles of the mass

fall into the relatively shallow notches 13 and the deeper notches 12 and are moved upwardly and rearwardly along the inclined walls of said notches. The grain thus will be separated from the chaff and straw and will fall into the sections 3 onto the bottoms of the latter and through the openings 9. The upper faces of the bottoms of the sections 3 are concavely curved transversely thereof so that all grain falling onto the bottoms of said sections will slide toward and through the openings 9. The upwardly and rearwardly inclined tongues 10 obstruct the forward movement of the grain and guide the grain through the openings 9. The downwardly and forwardly inclined tongues 11 deflect blasts of air from the fan 28 upwardly through the openings 9 so that such blasts of air will not only aid in separating the grain from the chaff but will aid in breaking up the mass of straw and chaff on the flanges of the sections 3 and will cause such mass to ride along the edges of the flanges of the sections 3. Also, the air currents which pass upwardly and rearwardly through the openings 9 will prevent any dust from falling through the openings and the grain thus will be cleaned. The imperforate forward end portions 7 of the bottoms of the sections 3 of the main separator floor extend forwardly of the front end of the screen 25 so that the separation of grain from the straw and chaff is well in progress before any of the grain is permitted to fall through openings in the bottoms of the sections 3. It of course will be understood that the screen 25 is of sufficiently coarse mesh to permit any grain that falls thereon to pass therethrough and to fall into the delivery chute 26. Any unthreshed or whole heads or pods of grain which reach the rearward end portions of the sections 3 will fall through the apertures 8. A return chute 31 for such unthreshed heads or pods of grain may be provided.

The separating action of the secondary floor 14 is substantially the same as that of the floor 2 and the purpose of the floor 14 is to supplement the action of the separator floor 2. The sections 15 of the secondary separator floor are of less width than the sections of the main separator floor. Grain which falls through the openings 9 in the bottoms of the sections of the main separator floor onto the secondary separator floor will pass freely through the openings in the bottoms of the sections of the secondary floor and the secondary separator floor will effect an additional separation of the grain from any chaff which may pass through the openings 9 of the main separator floor with the grain. Unthreshed heads or pods which fall through the cut away portions 8 of the sections of the main separator floor will fall through the openings 20 in the rearward end

portions of the sections of the secondary floor into the return chute or trough 31.

It of course will be understood that the openings in the bottoms of the sections of the separator floors may be of any suitable size and that the sections may be of desirable widths. For example, the sections and the openings in the bottoms thereof can be relatively narrow when designed for use to effect the separation of clover seeds from the straw and chaff and would be relatively wide when designed for use as a separator for beans.

Obviously, the invention is susceptible of embodiment in forms other than that which is illustrated in the accompanying drawing and I therefore consider as my own all such modifications and adaptations thereof as fairly fall within the scope of the appended claims.

I claim:—

1. In a separator, a floor comprising a plurality of juxtaposed channel-shaped sections disposed with the flanges thereof turned upward and having spaced openings in the bottoms thereof, the upper faces of the bottoms of said sections being concavely curved transversely thereof and said openings being located along the longitudinal median lines of said bottoms.

2. In a separator floor, a substantially U-shaped horizontal section disposed with the flanges thereof turned upward, the bottom of said section having spaced openings formed therein and being formed with an upwardly extending tongue at one edge of each opening and with a downwardly extending tongue at the opposite edge of said opening, said upwardly extending tongues having convexly curved edges.

3. In a separator floor, an elongated section substantially U-shaped in cross section, the bottom of said section having spaced openings formed therein along the longitudinal median line thereof and having an upwardly and rearwardly inclined tongue at the front edge of each of said openings and a downwardly and forwardly extending tongue at the rear edge of each opening, said tongues having convexly curved edges, the flanges of said section having notches in the edges thereof.

4. In a separator floor, an elongated sec-

tion substantially U-shaped in cross section, the bottom of said section having the upper 55 face thereof concavely curved transversely thereof and having spaced openings formed therein along the longitudinal median line thereof and having an upwardly and rearwardly inclined tongue at the front edge of 60 each of said openings and a downwardly and forwardly extending tongue at the rear edge of each opening, the flanges of said section having notches in the edges thereof, the bottom of said section being imperforate for a 65 short distance from the forward end thereof and being cut away for a short distance from the rearward end thereof.

5. In a separator floor, an elongated section substantially U-shaped in cross section, 70 said section having spaced openings in the bottom thereof, the flanges of said section having spaced relatively deep notches in the edges thereof and having series of spaced notches of less depth in the edges thereof between adjacent relatively deep notches, the notched portions of the sections between adjacent relatively deep notches being inclined 75 so that the respective second named notches between adjacent relatively deep notches are 80 located at different levels, each of said relatively deep notches and each of said more shallow notches having an inclined edge and a substantially vertical edge, all of said inclined edges being parallel and all of said 85 substantially vertical edges being parallel.

6. In a separator floor, an elongated section substantially U-shaped in cross section and having openings in the bottom thereof spaced longitudinally of the section, the 90 flanges of said section having spaced relatively deep notches formed therein, each of said notches having a substantially vertical edge and also another edge regularly inclined 95 for its entire length and extending from the base of the substantially vertical edge of one notch to the top of the substantially vertical edge of an adjacent notch, said inclined edges having regularly spaced relatively shallow notches formed therein, each 100 of said relatively shallow notches having an inclined edge parallel with the inclined edges of the deeper notches and a substantially vertical edge parallel with the substantially vertical edges of the deeper notches.

HENRY O. FREEMAN.
